[57] CLAIM

The ornamental design for an electronic scale with printer,
as shown and described.

DESCRIPTION

FIG. 1 is a perspective view of an electronic scale with
printer showing my design;

FIG. 2 is a front elevational view thereof;

FIG. 3 is a rear elevational view thereof;

FIG. 4 is a top view thereof;

FIG. 5 is a bottom plan view thereof;

FIG. 6 is a left side elevational view thereof;

FIG. 7 is a right side elevational view thereof; and,

FIG. 8 is a cross-sectional view thereof taken through line
8—8 of FIG. 4.
